(57) **CLAIM**

The ornamental design for a tie bar, as shown and described.

DESCRIPTION

FIG. 1 is a perspective view of an embodiment of a tie bar in accordance with the present invention.

FIG. 2 is a front view of the tie bar in FIG. 1.

FIG. 3 is a rear view of the tie bar in FIG. 1.

FIG. 4 is a top view of the tie bar in FIG. 1.

FIG. 5 is a bottom view of the tie bar in FIG. 1.

FIG. 6 is a left side view of the tie bar in FIG. 1; and,

FIG. 7 is a right side view of the tie bar in FIG. 1.

Broken lines are used to illustrate features of the tie bar which form no part of the claimed design.
